APPLIANCE FOR USE IN SHARPENING
SAFETY RAZOR BLADES

Alfred Leonard Walton, Blackpool, England

Application November 8, 1948, Serial No. 58,937
In Great Britain June 28, 1948

4 Claims. (Cl. 51—80)

1

The invention relates to appliances for use in sharpening or re-sharpening safety-razor blades of the double-edged variety, the invention being concerned with appliances of the type wherein the sharpening action is provided by the rotative movement of a plurality of abrading, stropping or polishing rollers (hereinafter referred to as sharpening rollers) in contact with an edge of the blade.

The object of the invention is to provide an appliance with improved means of operations, ensuring that the surfaces of the sharpening rollers in contact with the edges of the blade will always move, from the point of contact in a direction away from the said edges.

A further object of the invention is to provide an appliance having means whereby the edges of a double-edged blade can be sharpened from both sides in one operation, that is to say, without the necessity for changing the position of the blade.

A still further object of the invention is to provide an appliance in which the means in question are of simple form and reliable in operation.

The appliance according to the invention comprises a lower frame part, a superimposed cover part fitting slidably and detachably over the lower frame part, two spaced sharpening rollers carried in fixed positions by the lower frame part, the distance between the axes of rotation of the said rollers being substantially the same as the distance between the cutting edges of the blade to be sharpened, two rotatable sharpening rollers carried in fixed positions by the cover part and distanced apart to substantially the same extent as the sharpening rollers on the lower frame part and so mounted that each roller on the cover part has peripheral contact with the corresponding roller on the lower frame part when the two parts are placed together, means for locating a blade on the lower frame part so that its cutting edges will lie in the nips between the contacting sharpening rollers of the lower frame part and the cover part, and a single driving roller arranged for engagement with an outside surface and having a spindle engaged in and movable along horizontally disposed guide slots in the lower frame part, the guide slots being of such length relatively to the distance between the rollers on the lower frame part that when the said driving roller is applied to the said outside surface and the appliance is moved in either direction along the surface, the driving roller will rotate and move along the slots into engagement with the one or the other of the sharpening

2

rollers on the lower frame part, such rotary engagement causing this sharpening roller to rotate in a direction away from the corresponding cutting edge of the blade, and such rotation of the said sharpening roller causing rotation, also in a direction away from the same edge of the blade, of the corresponding sharpening roller on the cover part.

An embodiment of the invention is illustrated in the accompanying drawings in which:

Figure 1 is a cross-sectional view of the appliance, and

Figure 2 is a longitudinal sectional view corresponding to Figure 1.

15 The construction illustrated comprises a rectangular frame 1 in which two spaced sharpening rollers 2 and 3 are rotatively carried, the rollers being so disposed that their upper parts project above the frame and the distance between their axes is the same as or slightly greater than the width of the blade to be sharpened.

The end portions of the frame 1 are formed with depending lugs 4 and in each of these lugs there is provided a slot 5 which extends parallelly to a line passing through the axes of the rollers 2 and 3, and in which freely engages one end of a spindle 6 upon which is fixed a driving roller 7. The axis of the driving roller 7 lies below the axes of the sharpening rollers 2 and 30 3 and the driving roller is of such diameter that, by movement along the slots 5, it can be brought into surface contact with either the roller 2 or the roller 3, but not with both at the same time.

25 35 Means are provided for locating the razor blade so that the edges thereof to be sharpened lie in contact with the peripheral surfaces of the rollers 2 and 3 at the correct angle. To this end, the frame 1 is provided with a centrally 40 disposed cross-bar 8 carrying upwardly projecting spaced pins 9 over which the usual holes in the blade 10 can be engaged. The cross-sectional size of the pins is slightly less than the size of the holes in the blade to prevent the blade from 45 binding on the pins and to enable it to be easily applied and removed.

The appliance also includes a box-like casing 11 with an open base, the casing being of such dimensions that it can be placed, with a vertical sliding fit, over the frame 1, the latter thereby 50 entering the open base of the casing.

Two spaced sharpening rollers 12 and 13 are 55 rotatively mounted within the casing 11, these rollers being arranged the same distance apart as the rollers 2 and 3 and in parallelism there-

3

with, so that, when the casing is applied to the frame 1, the roller 12 will lie directly above and in contact with the roller 2, the same applying to the rollers 13 and 3.

The sharpening rollers 2, 3, 12 and 13 are made of or covered with a soft material such as leather or felt which may be dressed or impregnated with a suitable sharpening compound.

The driving roller can be made of any suitable material so long as it has the ability to cause rotation of either one of the sharpening rollers 2 and 3 when in contact therewith.

The appliance is used as follows:

The casing 11 (with its rollers 12 and 13) is lifted from the frame 1 and the blade to be sharpened is placed over the pins 9 so that it rests by its cutting edges on the peripheral surfaces of the sharpening rollers 2 and 3. The casing 11 is now fitted over the frame 1 so that the sharpening rollers 12 and 13 come to rest on the cutting edges of the blades, these edges being thereby engaged in the nips of the pairs of rollers. The casing is now held between thumb and finger and the driving roller 7 is presented to and pressed against a suitable flat surface such as that of a wall or table top, whereupon the appliance as a whole is moved to-and-fro on the said surface. Viewing Figure 1 for example, when the appliance is moved to the right, the driving roller 7 will be rotated clockwise, causing this roller to move bodily to the left, relatively speaking, by reason of the engagement of its spindle 6 with the upper edges of the slots 5, thereby bringing the roller into engagement with the sharpening roller 2. By further movement of the appliance to the right the driving roller will continue to rotate clockwise and thus impart an anti-clockwise rotary movement to the sharpening roller 2. By reason of the fact that the peripheral surfaces of the rollers 2 and 12 are resilient, the pressure applied to the casing 11 in the direction of the driving roller 7 will result in a slight flattening of the rollers at the contact point, thereby ensuring that the roller 12 will be driven in a clockwise direction from the roller 2, and this in spite of the fact that an edge of the blade lies in the nip of the rollers. Both rollers 2 and 12 will, thus, rotate in a direction away from the corresponding cutting edge of the razor blade, this edge being thereby sharpened from both sides simultaneously without fear of the rollers damaging the said edge or of the edge damaging the surfaces of the rollers.

When the appliance is moved to the left, the driving roller 7 will be rotated anti-clockwise, causing it first to travel bodily to the right, relatively speaking, again by reason of the engagement of its spindle 6 with the upper edges of the slots 5. The roller will thus be moved out of engagement with the sharpening roller 2 (which will thus cease to rotate) into engagement with the sharpening roller 3. By further movement of the appliance to the left, the driving roller will continue to rotate anti-clockwise and thus impart a clockwise rotary movement to the sharpening roller 3 which, in turn, for reasons already explained with reference to the rollers 2 and 12, will impart an anti-clockwise rotary movement to the sharpening roller 13. Hence, the rollers 3 and 13 will both rotate in a direction away from the corresponding cutting edge of the blade.

The amount of pressure exerted upon the cutting edges of the blade by the four sharpening

4

rollers will depend upon the degree of downward pressure applied to the casing 11 by the user when reciprocating the appliance.

In short, in the arrangement described, the act of reciprocating the appliance will cause the pair of sharpening rollers 2 and 12 to rotate while the other pair 3 and 13 is stationary, and vice versa.

I claim:

10. 1. An appliance for use in sharpening safety-razor blades of the double-edged variety, the appliance comprising a lower frame part, a superimposed cover part fitting slidably and detachably over the lower frame part, two spaced rotatable sharpening rollers carried in fixed positions by the lower frame part, the distance between the axes of the said rollers being substantially the same as the distance between the cutting edges of the blade to be sharpened, two rotatable sharpening rollers carried in fixed positions by the cover part and distanced apart to substantially the same extent as the sharpening rollers on the lower frame part and so mounted that each roller on the cover part has peripheral contact with the corresponding roller on the lower frame part when the two parts are placed together, means for locating a blade on the lower frame part so that its cutting edges will lie in the nips between the contacting sharpening rollers of the lower frame part and the cover part, a single driving roller arranged for engagement with an outside surface and having a spindle engaged in and movable along elongated guide slots provided in the lower frame part and extending in parallelism with a plane passing through the axes of the sharpening rollers on this part, said guide slots being of such length relatively to the distance between the sharpening rollers on the lower frame part that when the driving roller is applied to the said outside surface and the appliance is moved in either direction along said surface, the driving roller will rotate and move along the guide slots into engagement with the one or the other of the sharpening rollers on the lower frame part, such rotary engagement causing this sharpening roller to rotate in a direction away from the corresponding cutting edge of the blade, and such rotation of the said sharpening roller causing rotation, also in a direction away from the same edge of the blade, of the corresponding sharpening roller on the cover part.
20. 2. An appliance according to claim 1, wherein rotation of each sharpening roller on the cover part results solely from surface contact with the corresponding sharpening roller on the lower frame part.
30. 3. An appliance according to claim 1, wherein the lower frame part has an open top through which the sharpening rollers on this frame part partly project, and an open base from which the driving roller partly projects, and wherein the cover part is in the form of a box-like casing with an open base, the casing fitting slidably and detachably over the lower frame part.
40. 4. An appliance according to claim 1, wherein the blade-locating means comprise upwardly projecting pins carried by a bar on the lower frame part and adapted to be engaged in the usual holes in the blade.

ALFRED LEONARD WALTON.
